UNITED STATES PATENT OFFICE

HENRY T. PAISTE, OF PHILADELPHIA, PENNSYLVANIA, ASSIGNOR, BY MESNE ASSIGNMENTS, TO THE ARROW-HART & HEGEMAN ELECTRIC COMPANY, OF HARTFORD, CONNECTICUT, A CORPORATION OF CONNECTICUT

ELECTRIC FIXTURE

Application filed September 24, 1925, Serial No. 58,461. Renewed September 14, 1929.

My invention relates to certain improvements in electric fixtures of the type known as "candle fixtures," i. e., fixtures that are designed to simulate a candle.

5 In this type of fixture, there is a base, and, at the upper end, there is a socket for the lamp. Located within the structure is a skeleton frame that supports the socket.

One object of the invention is to attach 10 the frame to the socket member by a single means such as a screw.

Another object of the invention is to attach all of the parts forming the internal mechanism of the fixture by a single means.

15 A further object of the invention is to provide means for adjusting the skeleton frame so that it can be used in connection with candle parts of different lengths.

The invention also relates to other details, which will be fully described herein- 20 after.

This application is a revival of application Serial No. 690,840, filed February 5, 1924.

In the accompanying drawings:

25 Fig. 1 is a vertical sectional view of an electric candle fixture illustrating my invention;

Fig. 2 is a plan view of the socket;

Fig. 3 is a sectional plan view on the line 30 3—3, Fig. 1;

Fig. 4 is an inverted sectional view on the line 4—4, Fig. 1;

Fig. 5 is a perspective view showing the parts of the fixture detached;

35 Fig. 6 is an inverted perspective view of the non-conducting member, preferably of porcelain; and

Figs. 7 and 8 are detached perspective 40 views illustrating modifications of the invention.

Referring to the drawings, 1 is a bracket having a threaded portion 2 to which is attached the fixture 3. At the upper end of the fixture is a screw shell socket 4 for an electric lamp 5. Surrounding the fixture is an ornamental portion 6 of the fixture and a tubular section 7, which represents a candle. The socket 4 is made of pressed sheet metal having a screw thread of the ordinary type to receive the thread on the

electric lamp. The socket is surrounded preferably by a fibre tube 8. In the bottom of the socket is an opening 9, shaped as shown in Fig. 5, and by dotted lines in Fig. 2. Mounted on the bottom of the socket 55 is a terminal plate 10 that has an extension 11 in which is a binding screw 12.

13 designates a fibre washer that is mounted above the plate. 14 designates a metallic washer. 15 designates a screw, which confines the several parts and which forms the centre contact in the present instance. Under the socket 4 is a non-conducting block or insulating base 16 of porcelain, or other suitable material having a hole 17 for the passage of the screw 15. The block has a notch 18 at one side to receive the depending portion of the terminal 10. The block 16 is notched at 19 to receive the portion 21 of the terminal disk 20. This disk has a 70 threaded opening 22, which forms a nut for the screw 15. Between the non-conducting block 16 and the disk 20 is a non-conducting fibre disk 23, which is notched as shown at 24, Fig. 5. The terminals 11 and 21 pass 75 through the notches 24.

25, 25 designate two members, which form the skeleton frame or supporting bracket. Each of these members, as shown in Figs. 1 and 5, is made in two sections 26 and 27. 80 Each section is perforated, as at 28 and 29, respectively, for the passage of eyelets, rivets, or screws, by which the two parts can be adjustably secured together. On each member of the frame is a longitudinal flange 85 30. These flanges act as guides when the two parts are adjusted, and tend to hold the parts rigidly when a single eyelet is used in each member.

It will be noticed that the holes in one 90 pair of members are located closer together than the holes in the other pair of members so that minute adjustments are possible. The members 27 of the skeleton frame form an integral part of a ring 31, which has a 95 threaded portion 32 that is adapted to be screwed onto the threaded portion 2 of the bracket 1. The members 25 of the frame are separate. Each member has an inturned head 33 at its upper end. This head is shaped 100

as shown in Fig. 5 to fit the recesses 34 in the non-conducting block 16. The washer 23 is notched at 35 to receive the bodies of the members 35. The heads 33 are clamped onto the block 16 by the washer 23. The screw 15, when the parts are assembled, securely clamps the terminal disk 20 onto the disk 23. The single screw fastens all of the parts through which it passes.

10. In some instances, where fixtures of a standard size are manufactured, the skeleton frame need not be made adjustable. The frame, in this instance, can be made as shown at 25^a, Fig. 7, and has two members 27^a forming part of, or secured to, a ring 31^a, and having inturned heads 33^a, which can be located in the sockets of the non-conducting block 16.

As another modification, one part can be 20 slotted, as at 29^a, Fig. 8, and the other part can have a single hole 29^b for the passage of an eyelet, rivet, or screw. In this instance, one part is flanged on both sides, and the other part is arranged to fit the space between 25 the flanges.

By the invention hereinbefore described, it will be seen that the parts can be assembled and secured in their assembled position by a single means such as a screw, also that the 30 skeleton frame can be easily attached to the socket and can be made extensible to accommodate electric light fixtures of different designs.

I claim:

35. 1. An electric lamp socket comprising a laterally recessed insulating base, a screw shell socket contact arranged at one face of the base, a supporting bracket having attaching means arranged at the opposite face of 40 the base, a wire terminal extending from said screw shell contact into a lateral recess in the base, a second wire terminal insulated from the attaching means of the supporting bracket, and means, related to the center contact, 45 for engaging said second wire terminal to secure all of said parts to the base.

2. In an electric lamp socket, an insulating base laterally recessed to afford spaced channels, a pair of wire terminals respectively arranged at opposite faces of the base and projecting therefrom into said spaced lateral channels, a screw shell contact arranged at one end of the base and associated with one of the wire terminals, a center contact at said 55 end of the base and having an associated element passing through the base and engaging the other wire terminal at the opposite face of the base, together with a socket supporting bracket mechanically engaged by, but 60 insulated from, the terminal engaged by the center contact element.

3. The combination of a skeleton frame having inturned heads; a non-conducting block recessed to receive the heads; a notched 65 disk located under the heads; a terminal

plate forming a nut; a socket; a terminal plate located in the socket; and a centrally located screw extending through the several parts and into the terminal plate, said screw retaining the socket on the skeleton frame.

4. The combination in an electric fixture, of a skeleton frame made of two members, each member having two sections, the sections of one member sliding on those of the other member; a ring connecting the sections of 75 one lower member; means for attaching the members together; a socket; a non-conducting block; a disk, the upper member of the skeleton frame being clamped between the disk and the block; and a single securing 80 member for confining the parts together.

5. The combination in an electric fixture, of a skeleton frame made of two members, each member having a perforated section, the perforations of one member being spaced a greater 85 distance apart than those of the other member; means for securing the two members together; and a socket member mounted on the skeleton frame.

6. The combination in an electric fixture, 90 of a skeleton frame made of two members, each member having two sections, each section having a series of perforations, the sections of one member having perforations spaced a greater distance apart than the perforations of the sections of the other member; means for securing the two members together; a socket member; and a single securing means 95 for securing the socket member to the skeleton frame.

7. The combination in an electric fixture, of a skeleton frame having inturned heads at one end, a non-conducting block having recesses to receive the heads, a non-conducting disk located under the block and the heads of 100 the frame, a threaded terminal disk, a screw shell socket, and a screw extending through the non-conducting block and disk and adapted to be threaded in the terminal disk, said screw confining the several parts together.
